(57) **CLAIM**

The ornamental design for a battery device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top and right side perspective view of a first embodiment of a battery device showing our new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof;

FIG. 8 is a front, top and right side perspective view of a second embodiment of a battery device showing our new design, a top plan view being the same as FIG. 2, and a bottom plan view being the same as FIG. 7;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view of the first and second embodiments of the battery device, shown in an alternate state of use;

FIG. 14 is a top plan view of the first and second embodiments of the battery device, shown in an alternate state of use;

FIG. 15 is a top plan view of the first and second embodiments of the battery device, shown in an alternate state of use;

FIG. 16 is a top plan view of the first and second embodiments of the battery device, shown in an alternate state of use;

FIG. 17 is a top plan view of the first and second embodiments of the battery device, shown in an alternate state of use;

(Continued)

FIG. 18 is a top plan view of the first and second embodiments of the battery device, shown in an alternate state of use;

FIG. 19 is a top plan view of the first and second embodiments of the battery device, shown in an alternate state of use;

FIG. 20 is a top plan view of the first and second embodiments of the battery device, shown in an alternate state of use; and,

FIG. 21 is a top plan view of the first and second embodiments of the battery device, shown in an alternate state of use.

The broken lines shown in the drawings are for the purpose of illustrating portions of the battery device that form no part of the claimed design.
